CLAIM

The ornamental design for telephone instrument, as shown and described.

DESCRIPTION

FIG. 1 is a front, top and right side perspective view of a telephone instrument showing my new design in cradled relationship;

FIG. 2 is a top plan view thereof;

FIG. 3 is a right side elevational view thereof, the left side elevational view being substantially a mirror image thereof, except for the omission of the three buttons; and

FIG. 4 is a rear elevational view thereof.

The bottom of the instrument is plain and unarrayed.

FIG.1

FIG. 2

FIG. 3

FIG. 4
